R. BALMER

CHUTE GUARD

Filed March 5, 1924

Fig. 2.

15 Robert Balmer
BY Seward Davis
ATTORNEY.

UNITED STATES PATENT OFFICE.

ROBERT BALMER, OF TORONTO, ONTARIO, CANADA.

CHUTE GUARD.

Application filed March 5, 1924. Serial No. 697,106.

To all whom it may concern:

Be it known that I, ROBERT BALMER, a subject of the King of the United Kingdom of Great Britain and Ireland, and a citizen 5 of the Dominion of Canada, and a resident of the city of Toronto, in the Province of Ontario, in said Dominion, am the inventor or discoverer of certain new and useful Improvements in Chute Guards, of which the 10 following is a description.

My invention relates to guards for chutes adapted to protect a worker from accidents in places where the mouth of a chute, a trap-door, or like opening in a floor is employed 15 for charging material therethrough; it particularly concerns a guard for floor openings employed as the mouths of chutes in incinerators or garbage furnaces where material is manually drawn to a chute and adjacent which mouth the worker must stand 20 and across which he must reach with a long-handled rake to draw the waste, rubbish and garbage toward the chute-mouth for delivery therethrough to a fire-grate on a 25 lower level.

It has for its object the prevention of the workman from getting into the chute, by 30 guarding the mouth thereof from all sides by a particular form of grating which at the same time will not interfere with the work, and, on the contrary, will facilitate the handling of the heavy rakes customarily employed. A further object is the provision 35 in such a guard of means adapted to prevent the introduction of any over-sized object or any excess mass of garbage into the chute.

With the foregoing and other hereinafter recited objects in view, my invention consists in the structural means set forth and 40 described in the following specification, as illustrated in the accompanying drawings forming a part of this specification, wherein is shown a preferred structural embodiment 45 of my invention as applied to a garbage incinerator of the type illustrated in United States Letters-Patent Number 1,442,116, granted me January 16, 1923, and Number 1,460,566, granted me July 3, 1923.

In these drawings, Figure 1 is a vertical 50 sectional view of a conventionalized destructor, showing my invention as adapted thereto; Figure 2 is a vertical perspective view of my chute guard, and part of the chute associated therewith, viewed from the 55 position indicated by the line 2-2 in Fig. 1, looking in the direction indicated by the

arrow; and Figure 3 is a plan view thereof. Like reference characters indicate corresponding parts throughout.

1 is a furnace chamber and 2 a grate 60 therein. 3 is a waste storage bin having a floor inclined toward the doorway 4 thereof. 5 is the working floor. 6 is a chute in said floor opening at its bottom into the chamber 1 and having its mouth in the floor 5. 65 A hinged cover 7 may be provided at the mouth of the chute, as shown. It is shown closing the chute-mouth, and a drop or hopper bottom 8 is shown in open position, with a sliding cover 9 for closing the furnace 70 chamber and supporting the bottom 8. Beneath the floor 5 is an angle bar 10 rigidly supporting the guard elements or bars 11, 11, which are cross braced by the supporting base 12 resting on the bar 10 and to which 75 the elements 11 are detachably secured as by screw-bolts, to facilitate dismounting. An upper brace 13 is similarly attached to the bars 11. The elements 11 are preferably iron bars extending vertically the height of 80 the door 4, bent over at substantially right angles and extending across the mouth of the chute, and at their ends bent downwardly, leaving an opening 14 opposite the door 4. The height and width of this opening are less than the length of the shorter side of the mouth of the chute, if both are 85 rectangular; or the diameter of the mouth of the chute is greater than the longest linear dimension of the opening of the 90 guard, if the chute-opening is of circular or like form. The bars 11 with the supports 12 and 13 constitute a grating affording 95 openings between elements 11, between which elements a rake handle may be extended by the workman standing on the floor 5 in a station indicated approximately by the section line 2-2 of Figure 1. The rake may be thrust into the bin, the handle being between the bars, with freedom of vertical 100 movement of the handle. Similarly the rake may be drawn back and under the ends of the bars through the opening afforded without hindrance by the guard. At the same time, the cross brace 13 affords a bridge 105 upon which long-handled implements such as the garbage-rake may be slid forward and back, their weight being supported thereby. This cross-brace thus serves as a fulcrum and facilitates the handling of the heavy 110 implements. The opening 14 afforded by the guard on the side opposite and registering

with the doorway 4 permits a lateral range of play for the rake sufficient to handle and haul the rubbish, garbage or like waste as accumulated in the bin. The dimensions of 5 the opening 14 are such that any mass or object which can pass therethrough will likewise pass through the chute 6. Side members 15, 15 may be used if desired to complete the housing of the opening. The 10 raised door 7 assists in directing the material into the chute as a stop against which it may be raked, and the sides cooperate in this utility.

I have shown my invention as applied to 15 a garbage incinerator because it has especial value in protecting the workers who must stand close to an opening over a furnace in order to feed the material to its grate and who are liable to lean too far 20 over the opened chute in order to reach further back into the bin unless prevented. With an open chute unguarded, there is the further danger that the workman may lose his balance, if he leans over the chute, 25 by reason of the effect upon him of flame, heat or gases rising from the fire or by reason of slipping if the floor is wet.

While I have thus shown my chute guard as applied to an incinerator having a horizontal fire grate fed from above, I appreciate the broader utility of my invention and do not intend to be understood as limiting its application thereto or combination therewith, but desire it understood 30 to be useful with other structures presenting like or other hazards; nor do I intend to be understood as limiting my invention to the structural embodiment shown and described, since I believe it susceptible of 35 realization in variously modified forms within the definitions thereof given in the appended claims.

Having thus described and shown my preferred form, I claim:

45 1. A chute-guard composed of a plurality of vertically disposed members spaced apart and extending first upwardly, then horizon-

tally, and then downwardly, and terminating at a height above the floor equal to the inside length of their horizontal extension. 50

2. A chute-guard composed of a plurality of vertically disposed members spaced apart and extending first upwardly, then horizontally, and then downwardly, and terminating at a height above the floor equal to the inside length of their horizontal extension, 55 the two outside elements having each a side closure element associated therewith.

3. A chute-guard composed of a plurality of vertically disposed members spaced apart 60 and extending first upwardly, then horizontally, and then downwardly, and terminating at a height above the floor equal to the inside length of their horizontal extension, 65 and an upstanding base common to said members and detachable therefrom.

4. A chute-guard composed of a plurality of vertically disposed members spaced apart and extending first upwardly, then horizontally, and then downwardly, and terminating at a height above the floor equal to the inside length of their horizontal extension, 70 the two outside elements having each a side closure element associated therewith, and an upstanding base common to said members and detachable therefrom. 75

5. A chute-guard composed of a plurality of vertically disposed members spaced apart and extending first upwardly, then horizontally, and then downwardly, and terminating at a height above the floor equal to the inside length of their horizontal extension, 80 and a cross brace common to said members and constituting a tool rest.

6. In combination, a chute and a guard 85 therefor, the guard being composed of a plurality of bars extending upwardly and over the chute to be guarded and downwardly therebeyond, the downwardly projecting ends of the bars terminating above 90 a side of the chute and affording an opening whose longest dimension is less than the shortest dimension of the chute.

ROBERT BALMER.
